UNITED STATES PATENT OFFICE.

HENRY G. DIBELKA, OF CHICAGO, ILLINOIS, ASSIGNOR TO THE KINGSLEY-MILLER COMPANY, OF CHICAGO, ILLINOIS, A CORPORATION OF ILLINOIS.

ILLUMINATED GEAR-SHIFT-LEVER BALL.

Application filed October 19, 1925. Serial No. 63,256.

To all whom it may concern:

Be it known that I, HENRY G. DIBELKA, a citizen of the United States, residing at Chicago, in the county of Cook and State of Illinois, have invented certain new and useful Improvements in Illuminated Gear-Shift-Lever Balls, of which the following is a specification.

My invention relates to structural features of novelty in the mountings of illuminated balls for the ends of gear-shaft levers for automobiles and similar devices.

One aim of the invention is the production of a support for the ball or knob handle which incorporates an electric-switch, whereby the electric circuit of the lamp within the ball may be readily controlled.

A further purpose of the invention is the provision of a mounting or support of this kind which may be sold as an accessory and applied to the gear-shift levers of practically all, if not all, makes of cars.

An added aim of the invention is the production of an appliance of this character which is simple in structure, involving relatively few parts, and which may be manufactured at comparatively small cost.

To enable those trained in this art to understand how these and other advantages are obtained by the employment of the present invention, in the accompanying drawing, forming a part of this specification, and throughout the several views of which like reference characters have been used to designate the same parts, a present desirable and preferred embodiment of the invention has been illustrated in detail.

In these drawings:

Figure 1 is a longitudinal central section through the new appliance;

Figure 2 is an elevation of the same;

Figure 3 is a horizontal section on line 3-3 of Figure 1; and

Figure 4 is a similar section on line 4-4 of Figure 1.

Referring to these drawings it will be seen that the new device includes a main, cylindrical support or adapter 11 internally recessed and threaded at one end at 12 for easy application to the top, screw-threaded end of the gear-shift lever, not shown, in

place of the ball or handle with which it is usually fitted.

The opposite end of the body 12 is likewise provided with an internally-threaded passage 13 designed to accommodate the threaded shank or stem 14 of an incandescent electric-lamp bulb 15, such passage communicating with the larger cylindrical space 16 in the body.

A translucent or transparent ball 17, such as onyx, colored glass, or the like, has a cavity 18 therein provided partway of its depth or length with a bushing 19 cemented fixedly therein and having internal threads adapted to be screwed on to the exterior threads of the reduced end part 21 of the body 11.

When these elements are properly assembled, the incandescent filament of the lamp is at substantially the center of such encasing or enclosing ball or handle 17, the latter being effectively illuminated by the brilliant lamp.

In order to make the required electrical connection with the lamp, whereby it may receive its current, the cavity 16 has an insulation block 22 fixed therein by a screw 23, such element 22 accommodating a transverse, round, electrically-conductive pin or rod 24 with a head 25 located in a cut away section 26 of the block, a portion of the shank of the pin being exposed above registering flat surfaces 27 and 28 on opposite sides thereof, the inner or upper part of the block having an oblique wall or shoulder 29 provided for a purpose hereinafter specified.

As is clearly shown, the body 11, opposite the pin head 25, has a threaded opening 31 extended therethrough to detachably or demountably receive a threaded sleeve 32 around or encasing an insulating bushing 33 through which the end portion of the insulated wire 34 projects with its conductor end 35 in electrical contact with the exposed face of the head.

Thus it will be perceived that the electric wire and its mounting may be readily applied to or detached from the structure, by merely inserting or removing the associated parts 33 and 32.

The cylindrical cavity 16 also has or houses therein an oscillatory, reciprocatory,

insulation switch-body 36 designed to be turned or rocked and moved lengthwise slightly to open and close the circuit to the lamp-bulb by a screw 37 mounted therein and projecting outwardly through a slot 38 in the wall of the element 11 of greater width than the diameter of the screw to permit the reciprocation of the body 36 referred to.

10 This screw also projects through a hole in an externally-knurled sleeve 39 oscillatory around a reduced-diameter part of the member 11, all as is clearly indicated in Figure 1.

It will be perceived that turning of such sleeve causes a corresponding movement of the switch member 36, the latter having a metallic socket-member 41 molded therein which receives a telescoping contact 42 projected against the center end contact of the 20 lamp-bulb by an internal, expansion, coiled spring 43.

The switch element 36 of insulation material has a round-headed screw 44 disposed longitudinally thereof, projecting therefrom, 25 and in contact with the shell 41, the head of such screw by the turning of sleeve 39 being adapted to be shifted into and out of contact with the exposed part of the contact pin 24.

30 When the switch is in "off" position or open condition, the head of screw 44 is held in frictional engagement with the insulation surface 28 by reason of the tendency of the spring 43 to expand, whereby there is no 35 danger of the switch being jarred or vibrated into operative or "on" condition, the turning of the switch block in the direction of the opening of the switch being limited by the engagement of the contact screw 44 with 40 the oblique wall 29 or of the screw 37 with the end of its slot.

When the switch is turned into its "on" or operative position, the screw 44 rides slightly over the center of the pin 24, which 45 action is permitted by reason of the compressibility of the spring 43, and it is then held in contact with the pin by the tendency of the spring to expand or elongate, jarring of the movable screw from such desired relation being prevented because it is slightly beyond the highest part of the cross pin contact 24 and is consequently yieldingly held with the two screws in engagement which, of course, completes the circuit through the 50 lamp bulb, the latter having an outer threaded contact grounded on the body 11 as will be readily understood.

It will be perceived, therefore, that the 60 spring 43 performs the double function of always maintaining an efficient and effective contact with the lamp-bulb and of yieldingly maintaining the switch-body carrying the movable contact projected toward the stationary switch-element and permitting the 65 former to slide lengthwise the structure

somewhat during its oscillatory movements, whereby suitable pressure is exerted between the two contact elements of the switch when the latter is closed, and when the switch is in open condition, its movable parts are frictionally held against unintentional movement.

The appliance may be sold as an automobile accessory ready for easy application to the gear-shift lever, the adapter, of course, having suitable screw threads for mounting on the particular car intended.

In case the electric lamp-bulb becomes inoperative, as by reason of a broken filament, the onyx or other ball 17 may be unscrewed and taken off while the old bulb is being removed and a new one installed, whereupon the ball, constituting the knob or handle, may be screwed back into place.

It is to be understood that the present invention is not limited and restricted to the precise and exact details of structure illustrated and described, because these may be modified within comparatively wide limits without departure from the heart and essence of the invention as defined by the appended claims.

I claim:

1. In a gear-shift lever attachment of the character described, the combination of a hollow adapter designed to be mounted on the lever, an electric-lamp bulb socket on said adapter, a hollow ball on said adapter to enclose a bulb in said socket, an electric-conductor entering said adapter through its side wall, an electric-switch in said adapter in the circuit of said conductor and bulb, means on the exterior of said adapter to operate said switch, and means to prevent the switch from being jarred out of the position in which it has been set.

2. In a gear-shift lever attachment of the character described, the combination of a hollow adapter designed to be mounted on the lever, an electric-lamp bulb socket on the adapter including a movable contact designed to engage one of the terminals of a lamp bulb in said socket, an electric-switch in said adapter in the circuit of said socket and having a movable contact, means exterior to said adapter to permit the switch to be operated, an electric-conductor entering said adapter and electrically connected to said switch, and a spring acting on the movable contacts of both said socket and switch.

3. In a gear-shift lever attachment of the character described, the combination of a hollow adapter designed to be mounted on the lever, an electric-lamp bulb socket on said adapter, an insulation body in said adapter carrying a contact for a bulb in said socket and a switch contact in electrical connection therewith, means on the exterior of the adapter for moving said body, a sta-

tionary insulation member in said adapter, a switch contact thereon with which said first switch contact cooperates, and an electric conductor entering said adapter and in connection with said stationary switch contact.

4. In a gear-shift lever attachment of the character described, the combination of a hollow adapter designed to be mounted on the lever, an electric-lamp bulb socket in said adapter, an insulation body mounted in said adapter for reciprocation and oscillation and carrying a yieldingly-mounted contact for a bulb in said socket and a switch contact in electrical connection therewith, means on the exterior of the adapter for turning said body, a stationary insulation member in said adapter, a switch contact thereon with which said first switch contact cooperates, and an electric-conductor entering said adapter and in connection with said stationary switch contact.

5. In a gear-shift lever attachment of the character described, the combination of a

hollow adapter designed to be mounted on the lever, an electric-lamp bulb socket in said adapter, an insulation body mounted in said adapter for reciprocation and oscillation and carrying a spring-pressed contact for a bulb in said socket and a switch-contact in electrical connection therewith, means on the exterior of the adapter for turning said body, a stationary insulation member in said adapter, a switch contact embedded partially in said member with an exposed rounded portion cooperating with said first switch contact, the spring holding said movable insulation body frictionally against displacement both when the switch is in open and in closed positions, and an electric conductor entering said adapter and in electrical connection with said stationary switch contact.

In witness whereof I have hereunto set my hand and seal.

HENRY G. DIBELKA. [L.S.]
